UNITED STATES PATENT OFFICE.

CHARLES OSCAR NELSON, OF CLEVELAND, OHIO.

DESIGN FOR A HIGH-FREQUENCY ELECTRIC CABINET.

44,892.

Specification for Design.

Patented Nov. 18, 1913.

Application filed August 23, 1913. Serial No. 786,337. Term of patent 3½ years.

To all whom it may concern:

Be it known that I, CHARLES OSCAR NELSON, a subject of the King of Sweden, residing at Cleveland, in the county of Cuyahoga and State of Ohio, have invented a new, original, useful, and ornamental Design for High-Frequency Electric Cabinets, of which the following is a specification, reference being had to the accompanying drawing, forming part thereof.

Figure 1 is a front elevation of the cabinet, with an upper corner broken away. Fig. 2 is a plan view of the cabinet.

I claim—

The ornamental design for a high frequency electric cabinet, as shown.

CHAS. OSCAR NELSON.
